UNITED STATES PATENT OFFICE

PAUL JACK BURDE, OF VANCOUVER, BRITISH COLUMBIA, CANADA

DESIGN FOR A COMBINATION ILLUMINATED LICENSE-PLATE HOLDER AND DIRECTION INDICATOR FOR AUTOMOBILES

Application filed July 20, 1929. Serial No. 32,128. Term of patent 7 years.

To all whom it may concern:

Be it known that I, PAUL JACK BURDE, a subject of the King of Great Britain, and a resident of the city of Vancouver, in the Province of British Columbia, Canada, have invented a new, original, and ornamental Design for a Combination Illuminated License-Plate Holder and Direction Indicator for Automobiles, of which the following is a specification, reference being had to the accompanying drawing, forming part thereof,

The figure is a perspective view of a combination license plate holder and direction indicator showing my new design.

I claim:

The ornamental design for a combination license plate holder and direction indicator, as shown.

Dated at Vancouver, B. C., this 21st day of June, 1929.

PAUL JACK BURDE.
